DOUBLE DECK RAILROAD STOCK CAR BODY

Henry E. Keniston, Cincinnati, Ohio, assignor to Ortner
Freight Car Company, Cincinnati, Ohio, a corporation
of Kentucky

Filed Sept. 16, 1968, Ser. No. 13,554

Term of patent 14 years

Int. Cl. D12—03

U.S. Cl. D66—1

FIG. 1

FIG. 2

FIG. 3

FIG. 4

FIGURE 1 is a side elevational view of a double deck railroad stock car body embodying my new design.

FIGURE 2 is a plan view thereof.

FIGURES 3 and 4 are end views thereof.

The side of the stock car not shown is the same as the side shown.

I claim:

The ornamental design for a double deck railroad stock car body, substantially as shown and described.
